UNITED STATES PATENT OFFICE.

LEON DER SARKIS TASHJIAN, OF FRESNO, CALIFORNIA.

DESIGN FOR A CABINET FOR TOOTHBRUSHES.

Application filed August 13, 1926. Serial No. 18,733. Term of patent 14 years.

To all whom it may concern:

Be it known that I, LEON DER SARKIS TASHJIAN, a citizen of the United States, residing at Fresno, in the county of Fresno and State of California, have invented a new, original, and ornamental Design for a Cabinet for Toothbrushes, of which the following is a specification, reference being had to the accompanying drawing, forming part hereof.

In the drawing:

Fig. 2 is a side elevation of the same.

I claim:

The ornamental design for a cabinet for toothbrushes, as shown.

LEON DER SARKIS TASHJIAN.
